UNITED STATES PATENT OFFICE.

EDWIN N. LIGHTFOOT, OF NEW YORK, N. Y., ASSIGNOR TO THE CUTLER-HAMMER MFG. CO., OF MILWAUKEE, WISCONSIN, A CORPORATION OF WISCONSIN.

ELECTRIC HEATER.

1,403,331.

Specification of Letters Patent. Patented Jan. 10, 1922.

Application filed April 9, 1920. Serial No. 372,616.

To all whom it may concern:

Be it known that I, EDWIN N. LIGHTFOOT, a citizen of the United States, residing at New York, in the county of Bronx and State of New York, have invented new and useful Improvements in Electric Heaters, of which the following is a specification.

This invention relates to electric heater.

More particularly this invention relates to a flat electric heater having a resistor enclosed in but insulated from a sheet metal armor.

An object of this invention is to provide a rugged and durable terminal support for such a heater.

Another object is to provide a terminal support which also serves as a support for a cover box for the terminals.

Another object is to provide a terminal support which will facilitate the manufacture of heaters of which it forms a part.

Another object is to provide a projecting support for flat heaters on which all or part of the terminals may be mounted.

Another object is to provide an enclosed terminal support.

Embodiments of this invention are illustrated in the accompanying drawings, in which—

30 Fig. 1 is a side elevation of a heater provided with a terminal support carrying a terminal insulated from the support.

Fig. 2 is an enlarged longitudinal vertical section through the heater and its terminal support and terminal.

Fig. 3 is a plan of a blank terminal support.

Fig. 4 is a top plan of a heater in which the base of each terminal support forms a portion of one of the reenforcing plates of the flat heater.

Fig. 5 is a plan of the upper reenforcing plate with a terminal support formed integrally therewith and projecting from each end thereof.

Fig. 6 is a plan of a blank terminal support arranged to carry two terminals.

Fig. 7 is a plan of a blank terminal support provided with a perforated lug for co-

operating with and locking a cover box in position to enclose the terminal.

Fig. 8 is a side elevation of a heater with a cover box enclosing the terminal carried by the terminal support.

Fig. 9 is a top plan of the heater shown in Fig. 8.

Fig. 10 is a top plan of a heater equipped with another form of cover box.

Fig. 11 is a view of the terminal support employed in the heater shown in Fig. 10.

Fig. 12 is a vertical section on the line 12—12 of Fig. 10.

Fig. 13 is a plan of terminal support for carrying two terminals.

Fig. 14 is a perspective of a heater equipped with the terminal support of Fig. 13, and a co-operating cover box.

Fig. 15 is a plan of a terminal support for carrying four terminals.

Fig. 16 is a perspective of a heater equipped with the terminal support of Fig. 15.

Fig. 17 is a perspective of a heater shown in Fig. 16 with the addition of a cover box for the terminals.

Fig. 18 is a perspective of the insulating plate used in the cover box shown in Fig. 17.

Fig. 19 is a vertical section through the terminal support, one terminal and the cover box shown in Fig. 17.

Fig. 20 is an end elevation of the heater shown in Fig. 17 with a portion of the box and insulation broken away to show the terminals mounted upon the terminal support.

Fig. 21 is a plan of a terminal support which may be mounted upon the heater after the resistor has been enclosed in the armor.

Fig. 22 is a perspective of a heater equipped with a terminal support shown in Fig. 21.

Fig. 23 is a perspective of a heater shown in Fig. 21 equipped with a cover box for the terminals.

Fig. 24 is a perspective of the cover box shown in Fig. 23.

Fig. 25 is a perspective of a two piece insulating bushing employed to insulate the

electric conductors from the openings through which they enter the cover box.

Fig. 26 is a vertical section of the insulating bushing shown in Fig. 25.

5 Fig. 27 is a front elevation of the insulating bushing shown in Fig. 25.

Fig. 28 is a perspective of another form of cover box.

10 Fig. 29 is a front elevation of an insulating bushing for use with the cover box shown in Fig. 28.

Fig. 30 is a vertical section through the insulating bushing shown in Fig. 29.

15 Fig. 31 is an elevation of the cover box shown in Fig. 30 equipped with the insulating bushing shown in Figs. 28 and 29.

The heaters shown in the various figures of the drawings are of flat electric heaters.

20 Fig. 2 shows a heater made up of a resistor 37 wound about a core 38 of insulation. The resistor 37 is enclosed in a sheet metal armor made up of two reenforcing plates 35 and 40, the former being provided with flanges folded over the latter. The 25 resistor 37 is insulated from the enclosing armor by insulating strips 36 and 37 placed on opposite sides of the resistor.

Fig. 3 shows the form of terminal support for use with the heater shown in Figs. 1 30 and 2. This terminal support comprises a base 41 and a perforated extension 42.

35 If the heater is of the type in which the terminal supports are built in, that is, the base of each terminal support is clamped in position by the flanges of the lower plate, before the flanges of the lower plate 35 are folded over the upper plate 40, then a terminal support (Fig. 3) is placed on top of the insulating strip 39 at each end of the pressure plate 40. The flanges of the lower plate 35 are then folded over the upper plate 40 and the base of each terminal support.

40 The heaters after being thus formed may be put in a press for compressing them into 45 very compact structures.

45 After the heater has been compressed a hollow terminal rivet 43 may be mounted upon each terminal support. The periphery of the perforation in the extension 42 is struck up to provide greater separation between the terminal support and terminal. An insulating washer 44 placed on one side of the terminal support 42 insulates the resistor 37 and the one end of the terminal rivet therefrom. Another insulating washer 45 placed upon the other side of the terminal support 42 insulates the other end of the terminal rivet therefrom. The insulating washers 44 and 45 are clamped in position by expanding the ends of the terminal rivet over the washers, the end of the resistor 37 being clamped against the washer 44 by and into electrical contact with the adjacent expanded end of the terminal rivet.

When the terminal is mounted upon the support, the support may be left extending in the same plane with the enclosing armor or may be bent at an angle thereto.

Fig. 4 shows one terminal support having 70 a long base 50 and another terminal support having a short base 51 co-operating with the base 50 to form the upper reenforcing plate which takes the place of the reenforcing plate shown in Fig. 2.

75 Fig. 5 shows a terminal support having a base 52 which forms the upper reenforcing plate of the heater, and a perforated extension 53 formed at each end of the base for carrying the terminals.

80 Fig. 6 shows a terminal support having a short base 54 and a projection provided with two perforations 55 in which terminals may be mounted. This terminal support may be employed in a heater the two terminals of which are to be mounted at the same end thereof.

85 Fig. 7 shows a terminal support having a short base 56 provided with a perforated extension 57 and a perforated lug 58. This terminal support may be employed where it is desired to enclose the terminals mounted in the perforated extension 57.

90 Figs. 8 and 9 show a heater equipped with the terminal support shown in Fig. 7 95 and a cover box 59 enclosing the terminal carried by the support. The cover box is locked in place by a cotter pin 60 extending through the perforated lug 58 protruding through a slot in the top of the cover 100 box. An insulated conductor 61 extending through an aperture in the side of the cover box 59 is connected to the terminal. The conductor is clamped against the terminal by a bolt 48 extending through the hollow 105 terminal rivet and a cooperating nut 49. This insulated conductor 61 is further insulated from the cover box 59 by an insulating bushing 62.

110 Fig. 10 shows a circular cover box. The top of this cover box 65 is provided with 8 perforations 66 arranged in a circle about the center of the box. An opening 67 in the center of the top of this box and the perforations 66 permit the positioning of the cover box in any one of eight different positions so that the conductor to be connected with the terminal of the heater may approach from any desired angle and enter the cover box directly through the aperture in the side thereof. The terminal support employed with the circular cover box of Fig. 10 is shown in detail in Fig. 11. The 115 perforated extension of this terminal support is provided with two short lugs 71 and a longer perforated lug 70. The perforated lug 70 extends through the opening 67 in the top of the cover box 65 and the shorter lugs 71 extend through oppositely positioned perforations 66 in the top of the 120 cover box.

125 The terminal support is provided with two short lugs 71 and a longer perforated lug 70. The perforated lug 70 extends through the opening 67 in the top of the cover box 65 and the shorter lugs 71 extend through oppositely positioned perforations 66 in the top of the 130 cover box.

cover box. The lugs 71 and the registering perforations 66 serve to position the cover box on the heater and cotter pin 60 locks the cover box to the terminal support.

5 Fig. 13 shows a terminal support having a base 75 and an extension in which are provided two perforations 76 for mounting the terminals side by side. Two perforated lugs 77 are formed on the perforated extension of the terminal support.

10 Fig. 14 shows a cover box 78 employed with a heater equipped with the terminal support of Fig. 13. Four perforations 79 provided in the top of the box and positioned 15 90° apart permit the cover box to be mounted in any one of four positions. The electrical conductors extending through the opening 80 in the side of the box may therefore approach from either end or side 20 of the heater. The cover box is locked in place by cotter pins 60 extending through the perforated lugs 77.

25 Figs. 15 and 16 show an E shaped terminal support which may be mounted upon the heater after the other elements thereof have been assembled and the heater has been compressed. The base 81 of this terminal support rests on top of the upper reenforcing plate 40 while the ends 82 overlie the 30 flanges of the lower reenforcing plate 35. The ends 82 are rigidly fastened to the flanges of the lower plate by soldering, riveting, or spot welding. The extension 83 is provided with two perforated lugs 84 for mounting the cover box. The extension 83 is 35 provided with two perforated lugs 84 for mounting the cover box. The extension 83 may be bent at right angles to the base 81 before being mounted upon the heater.

40 Fig. 17 shows the cover 85 which co-operates with the terminal support shown in Figs. 15 and 16. Openings 87 and 86 are provided in the top and one side of the cover box 85 so the conductors may enter through either the top or side thereof.

45 Figs. 18 and 19 show an L shaped insulating plate which fits in the cover box with the bushings 89 registering with either the perforations 86 or 87. The insulating strip is held in proper position by the perforated lugs 84 extending through slots 90 or 91 and the aligned slots in the top of the cover box. The bushings carried by the insulating plate provide additional insulation between the entering conductors and the cover 55 box.

The terminal support in Fig. 19 carries an eyelet 92 insulated from the extension 83 of the support by the insulating washers

45. The ends of the eyelet 92 are expanded over insulating washers 45 to form a seat for a second eyelet 94 which clamps the resistor 37 against the eyelet 92.

50 Figs. 21 and 22 show a terminal support having a base 95 the ends of which are struck 60 up slightly for mounting on the flanges of

the lower reenforcing plate, and an extension 96 carrying oppositely laterally extending perforated ears 97 and a perforated lug 98. The perforations in the ears 97 are to receive terminal eyelets 92 which are suitably insulated from the ears by means of insulating washers. The upper reenforcing plate 40 extending beyond the end of the heater is perforated for receiving an insulated eyelet 99 by means of which the heater 75 may be mounted. The resistor 37 extends through registering apertures in the upper insulating strip and the reenforcing plate 40 to the terminals.

70 Fig. 23 shows a terminal cover box locked to the terminal support by a cotter pin extending through the perforated lug 98. The opening 100 in the side of the box is provided with a split insulating bushing 101 for more thoroughly insulating the entering 85 electrical conductor from the cover box. The insulating bushing 101 is shown in detail in Figs. 25, 26 and 27, while the cover box is shown separately in Fig. 24.

75 Figs. 29 and 30 show a single piece insulating bushing 105 which may be used with the cover box 106 shown in Fig. 28. On each side of the opening 107, through which the electrical conductors enter the box, a lug 108 is formed to provide means 95 for locking the insulating bushing 105 to the cover box as shown in Fig. 31.

80 The invention contained herein is, of course, susceptible of other embodiments and adaptations.

85 What is claimed is,

1. In an electric heater having a resistor separated from an enclosing armor by insulating strips, the combination of a terminal support comprising a base mounted upon the armor and provided with an extension, and a terminal connected to the resistor and carried by but insulated from the extension.

105 2. An electric heater having in combination a resistor, an enclosing armor therefor, insulating strips separating the resistor and the armor, a terminal support having a flat base mounted upon the armor and provided with an extension, and a terminal connected to the resistor and carried by but insulated from the extension.

110 3. In an electric heater having a resistor separated from an enclosing armor by insulating strips, a terminal support comprising a flat base mounted upon the armor and provided with an extension, and a terminal for the resistor clamped to and insulated from the extension.

115 4. An electric heater having in combination a resistor, an enclosing armor therefor, insulating strips separating the resistor and the enclosing armor, a terminal support having a base mounted upon the armor and provided with a perforated extension, an insulating washer on each side of the perfo- 120

125

130

- rated extension, and a terminal rivet connected to the resistor and extending through the perforated extension and washers to clamp the same together.
5. A heater having in combination a resistor, an armor enclosing the resistor, insulating strips separating the resistor from the armor, a terminal support supported by the armor, a terminal for the resistor insulated from and carried by the terminal support, a cover for enclosing the terminal, and locking means for locking the cover to the terminal support.
6. An electric heater comprising a resistor, 15 an enclosing armor therefor, insulating strips separating the resistor and the armor, a terminal support having a base supported by the armor and provided with an extension, a lug formed on the extension, a terminal for the resistor carried by and insulated from the extension, a cover for the terminal having an aperture through which the lug extends, and locking means engaging the lug to lock the cover to the support.
- 20 7. A heater having in combination a resistor, an enclosing armor therefor, insulating strips separating the resistor and the armor, a terminal support having a base supported by the armor and provided with an extension, a lug formed on the extension, a terminal for the resistor carried by and insulated from the extension, and a cover for the terminal having an aperture through which the lug extends so as to position the 25 cover over the terminal.
8. A heater comprising a resistor, an enclosing armor therefor, insulating strips separating the resistor and the armor, a terminal support having a base supported by the armor and provided with an extension, 40 positioning lugs and a perforated lug formed on the extension, a terminal for the resistor carried by and insulated from the extension, a cover for the terminal having apertures 45 with which the positioning lugs register and an aperture through which the perforated
- lug extends, and a pin extending through the perforated lug so as to lock the cover to the support.
9. A heater having in combination a terminal support, a terminal insulated from and carried by the support, a cover for the terminal held in position by the terminal support, an electric conductor connected with the terminal and extending through an opening provided in the cover, an insulating bushing for the opening held in position by the co-operation of the cover and the terminal support. 50
10. A heater having in combination a terminal support, a terminal insulated from and carried by the support, a conductor connected to the terminal, a cover for the terminal having an opening through which the conductor extends, and means for locking the cover to the terminal support. 60
11. A heater having in combination a terminal support, a terminal insulated from and carried by the support, a cover for the terminal, and a locking member co-operating with the terminal support so as to lock the cover in position. 70
12. A heater having in combination a terminal support comprising a base and an extension, a terminal insulated from and carried by the extension, a lug formed on the extension, and a cover for the terminal having an aperture with which the lug registers to position the cover. 75
13. A heater having in combination a resistor, a pair of plates forming an enclosure for the resistor, insulating strips separating the resistor from the plates, an extension for one of the plates, a terminal for the resistor insulated from and carried by the extension, 80 a lug formed on the extension, and a cover for the terminal having an aperture with which the lug registers to position the cover. 85

In witness whereof, I have hereunto subscribed my name.

EDWIN N. LIGHTFOOT.
